CLIMBER FOR POLES OF HARD MATERIAL

Cesare Castelli, Genoa, Italy

Application April 20, 1934, Serial No. 731,634
In Italy April 26, 1933

8 Claims. (Cl. 227—8)

The present invention has for its object improvements in the climbers for poles of metal or cement, i. e. for poles of material different from the wood whereof they were initially made; in other words, the invention relates to an improved device to be applied to the shoe of the person who has to climb up poles of metal or cement (for instance of the electrical lines).

Formerly the poles were made of wood and therefore the climbers could be formed with inward projections or teeth on their arms so that the latter might stick to the pole to a sufficient extent by means of said teeth, and enable the operator to stop at the desired height.

Apart from the consideration that the use of such climbers provided with arms formed with projections or teeth causes more or less a deterioration in the external surface of the said poles and sets up thereon notches that facilitate the penetration of the exterior dampness into the wood, it is a matter of fact that such climbers are unsuitable for climbing up poles made of material that does not permit penetration (and the consequent holding action) of the pins or teeth. This applies, particularly, for instance, to tubular metallic poles and cement poles. The use of climbers of the types mentioned above in connection with the said poles, presents a serious danger for the operator, inasmuch as there is a possibility for the latter to slip downward.

With a view to obviating such inconveniences, climbers have already been designed which, in place of the bent arm destined to encircle the pole, present a small metallic column at the lower end of which fits the foot of the operator, while at its upper end is fastened a leather belt or ring that is set around the pole before starting climbing up same. The use of such climbers presents however various inconveniences the most serious of which are the following: they prevent a complete freedom of movement of the feet and legs of the operator, on account of the fact that said feet and legs are substantially tied by a belt to the pole; they prevent passing obstructions on the pole, such as, for instance, pin crowns, brackets, etc.

Formerly the poles were of moderate height and therefore presented transversal dimensions not very different at the bottom and at the top. With the present types of very tall cement or metal poles, which present at the base dimensions which are considerably greater than those of the top, therefore there is the inconvenience that the climbers, arranged to embrace the pole at its base, are disposed greatly inclined when fastened to the

top of the pole and compel the foot attachment to assume a very inclined position, which is troublesome for the person utilizing the climbers.

In order to avoid such inconvenience, climbers have been devised which act as clamps, i. e. in which the arm is pressed by mechanical means in normal direction against the external surface of the pole while also the foot attachment is pushed, by the same or other mechanical means, against the opposite surface of the pole, the adherence between the climbers and the pole being solely dependent on the action of said mechanical means. This form of climber, in addition to being of complicated structure, presents a faulty and insufficient security due to the risk of the operator's slipping downwards along the pole should the aforesaid mechanical means fail to function properly.

The climber in accordance with the present invention obviates all these inconveniences thanks to the improvement consisting firstly in that a strong adherence is set up between the climber arm and the pole and between the outer surface of the foot receiving means and the pole itself, not by means of the aforesaid teeth, but by providing suitable coverings or appliances of material having a high frictional coefficient, on said parts. Such material may consist, of a composition, suitable for the purpose, as, for instance, rubber.

In one embodiment of the invention the climber arm presents an adherent rubber tubular covering and the part of the climber to which the foot is fastened presents a rubber piece on the side that has to come in contact with the pole. The inner section of the covering will preferably be non-circular and also the arm of the climber will have a corresponding transversal section in order to prevent the rubber pipe from rotating relatively to the climber arm.

Both the tubular covering and the rubber block can be replaced when unsuitable for the purpose, due to deterioration.

Further, the invention is carried out by giving the arm designed to embrace the pole and which ends, at the bottom, at the attachment for the foot, a shape which approaches that of a portion of helix, i. e. a shape whereby the free end of said arm will be placed higher than the end of said arm to which the attachment for the foot of the operator is applied. As such attachment is, necessarily, located outside the pole, the weight of the person will act on the climber as on a lever, thus compelling the climber to heavily press against the pole both in proximity to the foot

attachment and along the arm encircling the pole. It is obvious that the invention can be applied to any type of arm climber whether this arm is fixed or adjustable or replaceable, with regard to the part that has to be connected to the foot of the operator.

When the pole is not of considerable height, the sizes of its top and bottom section are not so different as to necessitate the use of an adjustable arm as the arm will act effectively without variation of its position relatively to the part where the foot is to be connected.

But when the metal or cement poles are of considerable height, the dimensions of the bottom section are so different from the dimensions of the top sections that a climber with non-adjustable arm is less effective because the attachment for the foot, when the climber engages with the top part of the pole, will assume a position greatly inclined relatively to the horizontal.

In this case, the climber according to the present invention embodies a further improvement on account of the fact that, for poles of considerable height, it is provided with means that provides for variation in the position of the under-foot relatively to the arm by displacing the attachment of the shoe relatively to the arm of the climber, thus enabling the workman to easily use the climber even when the poles are greatly tapered, said use being, however, always based on the lever operation mentioned above.

Thus; as the operator climbing up the pole must secure the grapplers to portions thereof decreasing in section, by adjusting the position of the arm to the attachment for the foot he will be permitted to adapt the proportions of the grapplers to those of the portion of pole where he has to stop, thus rendering the use of these grapplers safe. The invention will be more clearly understood from the following description and accompanying drawing, in which:

Figure 1 is an elevation showing the use of the invention for ascending a pole;

Fig. 2 is a perspective view of one form of the invention with parts broken away;

Fig. 3 is a detailed view;

Figs. 4 and 5 are elevations at right angles of another form of the device;

Figs. 6 and 7 are plan and side views, respectively of certain modifications, and

Figs. 8 and 9 are front and side views of the device as used in holding a ladder to a pole.

The climber according to the invention consists substantially of an attachment 1 for the foot, of a block 20 made of material possessing a high friction coefficient and of an arm 22 covered with a material which also possesses a high friction coefficient, the free end 21 of the arm being when the device is in use higher than its attachment 10 to the climber 1, the arm being substantially formed according to a helical line. The load P (weight of the person) applied to the attachment of the foot, Fig. 1, causes the block 20 to bear and press against the pole 23 in the direction of the arrow F'. This gives the climber the tendency to rotate in the direction of the arrow R and causes the arm 22 to press against the pole 23 in the direction of the arrow F''; the forces of friction that are caused by the forces in the direction of F' and F'' prevent the climber from slipping downwards.

Referring particularly to Fig. 2, 1 is the part of the grapplers that is connected to the foot of the operator by means of the belt 4 and the clasp 3. The arm 21, with squared trans-

verse section or in general with polygonal section, is connected to the part 1 and covered with a tubular element 22 of material such as rubber possessing a high frictional coefficient. On the side of the part 1 destined to face the pole, 5 is provided a swallow-tailed seat 19 wherein a block 20 of rubber or the like is applied and secured.

Fig. 3 shows on enlarged scale a further shape that can be given to the arm and the covering. 10 In said figure showing the end of the arm, the latter is indicated by 21' and has the conformation of a channel with swallow-tailed transverse section, inside which is located and rigidly secured the tail 22' of a longitudinal covering 15 22'' of material with high frictional coefficient (for instance, rubber).

In both cases, the grapplers will adhere to the pole thanks to the high frictional coefficient offered by the covering 22 or 22'' of the arm 21 (or of the arm 21') and the block 20 respectively. When the grapplers are not in engagement with the pole, the foot and leg of the operator will be entirely free to accomplish any movements and the adherence will be as perfect—and perhaps even more perfect—as it could be with the arm and cramp grapplers at present used for wood poles.

Referring particularly to the embodiment illustrated in Figs. 4 and 5, wherein the reference numbers are the same as those adopted in connection with the preceding figures, it will be noted that the under-foot 1 is formed at the bottom with a swallow-tailed guide 5 along which slide in the direction of the arrows 6 and 7, a sliding member 8 which presents the opening 9 wherein the end 10 of the arm 11 can be introduced; a fixing screw 12 prevents it from coming out. The sliding member 8 is provided with a pin 13 whereupon is mounted the lever 14 biased by a spring 15 in the direction of the arrow 16, i. e. in such a direction that its tooth 17 may engage with one of the notches 18 on the lower edge of the swallow-tailed guide 5. If the tooth 17 is disengaged from the notches 18 by means of the lever 14, the under-foot 1 can be slid in the direction, for instance, of the arrow 7 shifting it to the position indicated by dotted lines and adapting the grapplers to a pole section of lesser dimensions. Such adaptation can be accomplished manually as well as with the other foot of the person who has already effected a partial ascent along the pole this being done by pressing on the lever 14 with either the hand or the foot and thus releasing the tooth 17 from a notch and pushing the lever and member together to the desired position.

Such adjustment also serves to prevent the under-foot 1 from inclining too much relatively to the horizontal (as indicated at the top of Fig. 1) when the climber is fastened to the pole at a point of lesser transverse sections. In the case illustrated in Figs. 2, 4 and 5, the foot has such a position as not to be directed towards the pole.

On the contrary, in the case of the device illustrated in Figs. 6 and 7 the foot (indicated by dotted lines at 23), is directed towards the axis of the pole; in this embodiment the arm 11 is adjustable according to the arrows 6' and 7' and the under-foot 1 of the climber is provided with a fixed rubber block 20' held in position by the screw 12', and a block adjustable in position 20'' which is fixed in position by the screw 12'' engaging with one of the threaded holes 24. 75

In Fig. 7 there are also indicated the arrows P, F', R and F'', used in Fig. 1.

Though for descriptive reasons the present invention has been based on the foregoing spec-

- ification and the accompanying drawing, yet many modifications can be made in the embodiment of the invention; thus, for instance, the motion of the direction of the arrow 7 of the under-foot relatively to the arm 11 or vice versa (Figs. 4 and 5), depending upon the person climbing up, or descending down, the pole, can be made automatically or by a lever; the arm 11 may be constructed integral with the sliding member 8. The climber 22-21 with its block 20 can also find many other utilizations, such as, for instance (Figs. 8 and 9) for applying a ladder 25 to a pole 23 at any point of its length, the ladder being secured, at the bottom, against the pole by a retaining means 26; etc. etc. All these modifications and utilizations and others are to be considered as part of the invention as set forth in the following claims.

Having now particularly described and ascertained the nature of the present invention and in what manner the same is to be performed, what is claimed is:—

1. In climbers for hard material poles, the combination of an under-foot, a pressure block composed of a material of high frictional coefficient in relative proximity to the under-foot and disposed on that part of the under-foot which will contact with said pole, a pole embracing arm of helical shape rising from the under-foot and contacting the pole in a spiral, said under-foot, block and arm forming a lever-unit supporting by said under-foot the weight of the person, and pressing on the pole by rotation around the block, coverings on the block and on the arm, said coverings being of material having a high frictional coefficient causing the climber to adhere to the pole and prevent it from slipping downwards.

2. In climbers for hard material poles, the combination of an under-foot, a pressure block composed of a material of high frictional coefficient in relative proximity to the under-foot and disposed on that part of the under-foot which will contact with the pole, a pole embracing arm of helical shape rising from the under-foot and contacting the pole in a spiral having one end of said arm connected to the under-foot said end being lower than the free end of said arm, said under-foot, block and arm forming a lever-unit supporting by the under-foot the weight of the person, and pressing on said pole by rotation around the block, coverings on said block and on said arm, said coverings being of material having a high frictional coefficient in order to cause the climbers to adhere to said pole and prevent same from slipping downwards.

3. In climbers for hard material poles, the combination of an under-foot, a pressure block composed of a material of high frictional coefficient in relative proximity to the under-foot, a pole embracing arm with non-circular transverse section, the under-foot, the block and the arm forming a lever-unit supporting the weight of the person and pressing on said pole by rotation around said block a tubular covering on said arm of high frictional coefficient in order to aid in preventing the covering from rotating relatively to the arm and to cause the climbers to adhere to said pole and to prevent same from slipping downwards.

4. In climbers for hard material poles, the

combination of an under-foot, a pressure block composed of a material of high frictional coefficient in relative proximity to the under-foot, a channel shaped pole embracing arm the channel transverse section of which has its opening towards the interior of said arm, said under-foot, said block and said arm forming a lever-unit supporting the weight of the person and pressing on the pole by rotation around the block a strip of material of high frictional coefficient inserted and retained in the hollow of said channel shaped arm, to aid in preventing the covering from going out relatively to the arm and to cause the climbers to adhere to said pole and to prevent same from slipping downwards.

5. In climbers for hard material poles, the combination of an under-foot, a pressure block composed of a material of high frictional coefficient in relative proximity to said under-foot and disposed on that part of the under-foot which will contact with the pole, a pole embracing arm of helical shape rising from the under-foot and contacting the pole in a spiral rigidly connected to said under-foot, said under-foot, block and arm forming a lever-unit supporting by said under-foot the weight of the person, and pressing on the pole by rotation around said block, of coverings on said block and on said arm, said coverings being of material having a high frictional coefficient to aid in causing the climbers to adhere to said pole and prevent same from slipping downwards.

6. In climbers for hard material poles, the combination of an under-foot, a pressure block composed of a material of high frictional coefficient in relative proximity to the under-foot and disposed on that part of said under-foot which will contact with said pole, a pole embracing arm of helical shape rising from the under-foot and contacting the pole in a spiral, means slidably and detachably connecting said arm to said under-foot, said under-foot, block and arm forming a lever-unit supporting by the under-foot the weight of the person, and pressing on said pole by rotation around said block, coverings on said block and on said arm, said coverings being of material having a high frictional coefficient in order to cause the climbers to adhere to said pole and prevent same from slipping downwards.

7. In climbers for hard material poles, the combination of an under-foot, a pressure block composed of a material of high frictional coefficient in relative proximity to said under-foot and disposed on the part of said under-foot which will contact with said pole, a supporting member, a pole embracing arm connected to said supporting member, of helical shape rising from the under-foot and contacting the pole in a spiral separate from said under-foot, of slidable means on said supporting member and on said under-foot, retaining means for said supporting means on said under-foot, said under-foot, block and arm forming a lever-unit supporting by said under-foot the weight of the person, and pressing on said pole by rotation around said block, coverings on said block and on said arm, said coverings being of material having a high frictional coefficient to aid in causing the climbers to adhere to the pole and prevent same from slipping downwards.

8. In climbers for hard material poles, the combination of an under-foot, a pressure block composed of a material of high frictional coefficient in relative proximity to said under-foot and disposed on that part of said under-foot which

will contact with the poles, a pole embracing arm of helical shape rising from the under-foot and contacting the pole in a spiral, said under-foot, block and arm forming a lever-unit supporting by said under-foot the weight of the person, and pressing on the pole by rotation around said block, of coverings on said block and on said arm, said coverings being of material having high

frictional coefficient to aid in causing the climbers to adhere to the pole and prevent same from slipping downwards, means for regulating the reciprocal position of the under-foot and of the arm in order to maintain the under-foot in substantially horizontal position, said means comprising a lever pivotally attached to the arm.

CESARE CASTELLI.
